CLAIM

The ornamental design for a square plastic piece with fissures which allow the vertical, ortogonal and oblique joint with the same square plastic pieces for a tridimensional construction of fantasy, as shown and described.

DESCRIPTION

FIG. 1 is a side view of square plastic piece with fissures which allow the vertical, ortogonal and oblique joint with the same square plastic pieces for a tridimensional construction of fantasy showing my new design, all other sides being identical; and,

FIG. 2 is a front view thereof, the rear view being a mirror image thereof.

1 Claim, 2 Drawing Sheets

FIG. 1

FIG. 2
